A. L. WAGSTAFF

HINGE

Filed Aug. 24, 1920

UNITED STATES PATENT OFFICE.

ANDREW L. WAGSTAFF, OF KANSAS CITY, MISSOURI, ASSIGNOR, BY MESNE ASSIGNMENTS, TO WAGSTAFF BOX MFG. CO., OF KANSAS CITY, MISSOURI, A CORPORATION OF MISSOURI.

HINGE.

Application filed August 24, 1920. Serial No. 405,641.

To all whom it may concern:

Be it known that I, ANDREW L. WAGSTAFF, a citizen of the United States, residing at Kansas City, in the county of Jackson and 5 State of Missouri, have invented certain new and useful Improvements in Hinges, of which the following is a specification.

My invention relates to improvements in crates, boxes, trunks and other containers, 10 and the important features of the invention reside more particularly in special reinforcement and other fittings of the lid to hold the same firmly in position upon the container and prevent said lid from being 15 loosened or pulled off its hinges.

In the accompanying drawing:

Fig. 1 is a perspective view of a crate equipped with the fittings constituting the invention.

20 Fig. 2 is a broken cross sectional view taken on line II—II of Fig. 1.

Fig. 3 is a detail rear elevation of one of the hinges on a fragmentary portion of the crate.

25 Fig. 4 is a detail perspective view of a portion of one of the inner reinforcing members, together with an abutment plate against which the former bears when the lid of the crate is in closed position.

30 In the drawing I have shown the invention applied to a rectangular crate having end walls 2 and 4, side walls 6 and 8, a lid 10 and a bottom 12. A handhold 14 is provided in each of the end walls 2 and 4 in order that the crate may be easily grasped and carried around.

One of the important features of the invention resides in a plurality of metallic straps 18, which are secured to the lid 10 and 35 formed into integral hinge members at one end as indicated at 20. The hinge members 20 engage around U-shaped hinge members 22, the ends 23 of which are bent outwardly and pass through holes in retaining plates 24 to which they are riveted. The retaining plates 24 are secured to the back wall 8 of the crate by rivets 26 or other suitable means, thus insuring a strong construction, and are pressed outwardly as indicated at 45 27 to provide recesses to receive and sustain the vertical arms of the hinge members 23.

A reinforcing member 30, constituting a part of the invention, and having downturned terminals 32, is secured to the inner

surface of the lid by suitable fastening devices such as rivets 34, which also pass upwardly through the central metallic strap 18, thus holding the two firmly together on opposite sides of the lid 10.

Abutment plates 38 are secured to the back and front walls of the crate, against which the downturned terminals 32 bear when the lid 10 is closed, thus serving to hold said lid firmly in place against side stresses. One abutment plate 38 is secured 65 to the rear wall 8 of the crate by the rivets 26, which also secure the retaining plates 24 in place as above stated. The other abutment plate 38 is secured to the front wall 6 of the crate by rivets 39. Plates 38 are preferably placed against the inner surface of the back wall 8 at points opposite the endmost retaining plates 24 to prevent the rivets 26 extending through the plates from being pulled out through said back wall 8 when 75 the hinges of the lid 10 are subjected to stresses.

In order to secure the lid 10 in closed or locked position, the forward end of the central strap 18 is bent downwardly to form a 80 tongue 42 which passes through a keeper 44 secured to a plate 48, which in turn is fastened firmly to the front wall 6 of the crate by the rivets 39.

A spring catch 52 is secured to the tongue 85 42 by suitable means such as rivets 54, said catch 52 having a curved intermediate portion 56 to engage over the keeper 44 and its end 58 being bent slightly outwardly so that on coming down in contact with the keeper 90 44 it will be forced outwardly, and on moving further down will spring into locked position as shown on Figs. 1 and 2.

When it is desired to lock the crate so that it cannot be opened by an unauthorized 95 person a seal (not shown) is employed, one end of which passes through a small perforation 60 in the end of the spring catch 52 and through a similar perforation 62 in the tongue 42, thus locking the two members 100 firmly together.

While it is preferable to extend the metallic straps 18 across the lid as shown, where a less substantial structure may be used the two endmost straps 18 may be shortened 105 to extend only part way across said lid 10, and the intermediate strap 18 may be made in two pieces, one piece having the hinge

members 20 and the other the tongue 42. Likewise the member 30 may be made in two pieces.

From the foregoing it will be understood that I have provided strong and durable crate fittings not likely to work loose or break, and while I have shown the preferred form of the invention, I reserve the right to make such changes as properly fall within the spirit and scope of the claims.

Have thus described my invention, what I claim and desire to secure by Letters Patent, is:

1. A hinge comprising a plate having elongated recesses, a strap and a member hinged to the strap and having arms in the recess in the plate, the ends of the arms passing through the plate, whereby the strap and plate will be hingedly secured together.
2. A hinge comprising a retainer plate adapted to be secured to the rear wall of a container and provided with recesses, and a U-shaped hinge member having arms disposed within the recesses and out-turned ends passing through the retaining plate and secured thereto.
3. A hinge comprising two complementary members and means for securing them together, one of the complementary members consisting of a plate having parallel recesses, the other member consisting of a strap, and means for connecting the plate

and the strap consisting of a U-shaped member swingingly secured to the strap and having arms in the recess, the ends of the arms being bent at angles to the main portions of the arms to project through openings in the plate, whereby the plate and the strap will be secured together.

4. A hinge for containers provided with lids, the hinge comprising a retaining plate to be secured to the rear wall of the container, a metallic plate in spaced relation with the retaining plate and adapted to bear against the inner face of the rear wall of the container, and a U-shaped hinge member having arms disposed within recesses in the retaining plate and having out-turned ends passing through the retaining plate and secured thereto.

5. The combination with a plate having elongated recesses, a strap, one end of which is provided with a hinge member, and a U-shaped member connected to the hinge member of the strap and having arms projected through the recesses, the ends of which extend through openings on the plate.

In testimony whereof I affix my signature, in the presence of two witnesses.

ANDREW L. WAGSTAFF.
